UNITED STATES PATENT OFFICE.

HERBERT E. WHITE, OF YOUNGSTOWN, OHIO, ASSIGNOR TO THE GENERAL FIREPROOF-
ING COMPANY, OF YOUNGSTOWN, OHIO, A CORPORATION OF OHIO.

SHEET-FEEDING PROCESS FOR METAL-EXPANDING MACHINES.

1,230,635.

Specification of Letters Patent. Patented June 19, 1917.

Application filed September 4, 1913. Serial No. 788,155.

To all whom it may concern:

Be it known that I, HERBERT E. WHITE, a citizen of the United States, residing at Youngstown, in the county of Mahoning and State of Ohio, have invented certain new and useful Improvements in Sheet-Feeding Processes for Metal-Expanding Machines, of which the following is a specification.

10 This invention relates to a novel and practical sheet-feeding process for metal expanding machines, and has for its object to provide a speedy and economical method of handling slotted metal sheets, for expanding 15 operations, involving a substantially continuous process of feeding the sheet with a minimum handling thereof on the part of the operator, thereby permitting the manufacture of a uniform product very rapidly 20 and on a large scale.

To this end, the invention has in view a process of sheet-feeding for metal expanding machines that entirely obviates the delay and other objections incident to the feeding, 25 one at a time, of single slotted metal sheets to an expanding mechanism, and instead thereof provides a way whereby the sheets may be fed in a substantially continuous manner with the desirable result of the 30 sheets themselves acting to automatically feed or enter one another into the expanding mechanism, and to discharge an expanded sheet from the latter.

In carrying out the process, any suitable 35 instrumentalities or mechanisms may be employed which are available, or can be adapted, for the purpose, so for illustrative purposes there are only shown in the drawings, diagrammatically, such views as may be necessary 40 for a full understanding of the novel manipulation of the slotted metal sheets to provide for a substantially continuous expanding operation within and through a stationary die-pass.

45 In these drawings,

Figure 1 is a detail perspective view illustrating the starting of the first slotted sheet into the pass between stationary co-acting die elements.

50 Fig. 2 is a side elevational view illustrating a pair of stationary co-acting expanding dies such as I prefer to use, and successive overlapped slotted sheets being fed to and through the die-pass.

55 Fig. 3 is a top plan view of the arrange-

ment of parts shown in Fig. 2, with the upper die member removed.

Fig. 4 is an enlarged detail cross sectional view on the line 4-4 of Fig. 2, illustrating the cross sectional characteristics of the stationary die-pass through which the slotted sheet slidably moves under the action of the feeding means therefor.

Fig. 5 is a perspective view illustrative of three overlapping slotted sheets showing all 65 of the stages of development thereof, that is, the non-expanded slotted sheet before it enters into the die-pass and having its advancing end lapped upon the inside of the rear end of the sheet within the pass; the slotted 70 sheet in advance thereof which is in course of its passage through the pass, and is therefore partly expanded; and, the third sheet which has reached its full development for 75 the greater portion of its area and is interlocked at its rear end portion with the front portion of the second sheet referred to.

Fig. 6 is a bottom plan view of the upper die, illustrating by dotted lines the direction of movement of the strands against the 80 series of inclined steps or shoulders.

Fig. 7 is a detail perspective view illustrating more plainly the nesting interlock of the opened meshes of the overlapping metal 85 sheets.

Fig. 8 is a similar view illustrative of the manner in which the overlapping of the sheets at the starting ends of the dies causes the slotted sheet within the die to act as a 90 feeder for entering a corner of the next following sheet into the die-pass.

Like reference characters designate corresponding parts in the several figures of the drawings.

In carrying out the present invention, the 95 metal sheets designated by the reference letter A, are preliminarily slotted by any suitable slitting machine or apparatus which produces therein parallel lines of interrupted slits arranged alternately in adjacent rows, the alternate or staggered disposition of the slits in adjacent rows serving to provide an uncut connecting neck a between the mesh-forming strands in adjoining rows.

100 As indicated, a distinctive feature of the present invention resides in a novel process or method of sheet-feeding for metal expanding machines, in order to provide a substantially continuous process that will 105 require a minimum handling of the sheets on 110

the part of the operator, and at the same time will provide for a substantially continuous sheet-feeding operation. In order to best illustrate this sheet-feeding process, 5 I have selected for purposes of illustration a form of die-pass representing one type of expanding mechanism with which the invention may be associated. This die-pass is designated generally by the reference letter 10 P, and constitutes the working interval or space between a pair of stationary co-acting dies 1 and 2 respectively. These co-acting dies preferably possess the structural and functional characteristics of the dies 15 closed in my former Patents Nos. 895,923, dated Aug. 11, 1908, and 1,061,953, dated May 13, 1913. That is to say, the said spaced-apart dies are provided upon their opposing faces with a series of laterally and 20 diagonally extending shoulders 3 and 4 respectively, which are adapted to be engaged by, and guide, the unslotted portions a of the metal sheet to one side, thereby opening the slits into meshes. While the lower die member 25 3 is of substantially the same structural formation as the upper die member, its function is to hold the slotted and partially expanded sheet in position for positive engagement with the shoulders or steps of the 30 upper die member against which the material presses and bears as it slides through the pass P under the impulse of the feeding elements 5, which latter may consist of a series of feeding rolls, as diagrammatically indicated, and as fully disclosed in my former 35 patents aforesaid.

In addition to the feature of the stationary die having a series of laterally and diagonally extending steps or shoulders 3-4, it 40 will be observed that the pass P, between the separate die members, extends obliquely in a direction longitudinally of the dies as shown in Fig. 2 of the drawings, and obliquely in a direction transversely of the dies as shown in Fig. 4 of the drawings. This disposition of the die-pass provides for producing an expanding action that runs successively from one corner of the sheet to the diagonally opposite corner, and further, on account of the lateral obliquity of the pass P, the same has an upward trend from one side to the other as shown in Fig. 4, with the result of compelling the uncut portions a to bear firmly against and closely follow the 55 shoulders of the upper die member 1.

The relation of the steps 3 and 4, in a cross-section of the die members 1 and 2, is plainly shown in Fig. 4 of the drawings. It will be observed that the upper expanding die 1 projects outwardly beyond the lower guiding die 2, as at 6, so as to successively interpose the various shoulders, formed by the inclined steps, into the path of the unslotted portion of the metal sheet 60 as it moves through the machine. Still re-

ferring to Fig. 4 of the drawings, it may be noted that the vertical distance between what may be termed the horizontal faces x, x, of the upper and lower die members, is a little wider than the width of single uncut 70 strands, while the vertical depth of the passage provided between directly opposing shoulders or steps 3 and 4 of the upper and lower die members, is slightly greater than the width of two strands at the connecting 75 neck a. The horizontal distance between the shoulders is the same as the width or size of the meshes, but all of these several distances are subject to variation and adjustment as particularly mentioned in my 80 former Patent No. 1,061,953.

In the illustrated embodiment of the invention, the slotted sheets are fed to the machine in a vertical plane, and in order to enter the first sheet into the starting end of 85 the pass P, the front upper corner of the sheet is bent laterally, and opened sufficiently, as indicated at 7, to permit the operator to enter the uncut strands at this corner into the pass against the first of the shoulders or steps of the die. After thus preliminarily opening the front upper corner of the first sheet and starting it into the die-pass, the feeding means of the machine will then pick up the sheet and move it longitudinally of the die, with the result of causing the unslotted strands to successively, progressively, and slidably engage the shoulders, and to be laterally guided thereby through the die-pass. This action serves to 90 open the slits into meshes. 100

As indicated, as the sheet begins to feed through the die-pass, the die elements (steps or shoulders) first operate upon one corner of the sheet and successively expand a greater number of strands until the full width of the sheet is reached. As the last portion of the sheet feeds through the machine, the number of meshes acted upon successively decreases until the diagonally 110 opposite corner, to that starting in, is expanded in the last portion of the travel. 110

In order to maintain the continuity of operation in the process so that it may be carried out speedily, the overlapping relation of the ends of the separate slotted sheets is essential, in effect making a continuous sheet that is being fed to and through the die-pass. This overlapping of the sheet ends is particularly important for 115 feeding-in purposes. Also it is important to provide for this overlap in such a manner that the following sheet, about to enter the die, has its advancing end disposed at the inside of the rear end portion of 120 the sheet ahead which is in the machine. Accordingly, the front end of said following sheet lies between the side of the die and the sheet within the die, so that as the rear upper corner of the latter sheet moves into 125 130

the die-pass, such corner will forcibly open the top upper corner (as at 8 in Fig. 8) of the following sheet so as to automatically enter it into the receiving end of the die-pass in a manner similar to the manual starting of the first sheet.

By reason of this overlapping of successive slotted sheets to provide for automatic insertion of the same into the receiving end 10 of the die-pass, a further practical result is effected, namely, that of causing the expanded portions of overlapped sheets, within the die, to become interlocked in nested relation, as indicated generally by 15 the letter I in Figs. 5 and 7 of the drawings. This interlocking of the meshes where adjoining sheets overlap, serves to cause the completely expanded sheet to be fully and freely ejected from the die-pass 20 by the sheet following.

I claim.

1. In the art of expanding slotted sheet metal, the process which consists in starting the opening of the strands in the following 25 blank, before the blank in advance thereof has passed from the expanding mechanism, by feeding the blanks with their ends in overlapped engagement.

2. In the art of expanding slotted sheet 30 metal, the hereindescribed process which

consists in starting the opening of the strands at a corner of the blank, before the blank in advance thereof has passed from the expanding mechanism, by feeding the blanks with their ends in overlapped engagement. 35

3. In the art of expanding slotted sheet metal, the hereindescribed process which consists in causing a rear corner of the blank within the expanding mechanism to 40 communicate a deflecting pressure upon an advancing corner of the following sheet to start the opening of the strands in the latter.

4. In the art of expanding slotted sheet 45 metal, the hereindescribed process which consists in causing the sheet within the expanding mechanism to exert a deflecting pressure upon a corner portion of the following sheet to thereby initiate the opening 50 of the strands in the latter and to cause a registering interlocking of the two sheets.

In testimony whereof I hereunto affix my signature in the presence of two witnesses.

HERBERT E. WHITE.
